UNITED STATES PATENT OFFICE.

CHARLES HARRISON PIERCE, OF WADENA, MINNESOTA.

LIMB BRACE.

Application filed December 14, 1926. Serial No. 154,734.

This invention relates to an improved limb brace for use in association with fractures and dislocations occurring in the lower leg, the upper leg above the knee, or at the hip joint.

My principal aim is to generally improve upon inventions of this class by providing one including an exceptionally efficient and dependable structure which is easy to apply and adjust and which is highly reliable in equalizing strain, distributing stresses, maintaining the bone sections in proper alignment, and yet allowing freedom of movement under certain predetermined conditions.

One of the outstanding features of the invention however is the employment of a comparatively light weight yet durable structure used in connection with plaster of Paris casts for the purpose of anchoring, together with means for exerting axial or longitudinal strain for insuring proper relationship of fractured or broken parts in order that they may resume normal positions after treatment.

An equally important feature is in the provision of a structure which is so associated with the limb as to permit inspection and treatment without undue interference.

In brief, what I propose is an efficient structure which permits the desired passive motion, and makes for excellent anatomical and functional results.

The particular detail and the relative arrangement and association will become apparent from the following description and drawing.

In the accompanying drawings forming a part of this application and in which like numerals are employed to designate like parts throughout the same:—

Figure 1 is a side view of one embodiment of the invention.

Fig. 2 is an enlarged detail view in section and elevation showing this embodiment of the invention as it is applied.

Fig. 3 is a perspective view of one of the details,

Figure 4 is a side elevation of a supplementary part used under certain conditions,

Fig. 5 is a front elevation of a slightly modified embodiment of the invention, showing the use of auxiliary extensions and the part represented in Fig. 4,

Fig. 6 is a side view of Fig. 5 showing the method of mobility and angularity of movement,

Fig. 7 is a front elevation of a further modification of the invention showing the employment of calipers,

Fig. 8 is a side view of Fig. 7,

Fig. 9 is a perspective view of an important factor forming part of all of the embodiments of the invention,

Fig. 10 is a perspective view of another one of the details,

Fig. 11 is a front view of a still further embodiment of the invention used in connection with a fracture of a different type.

Fig. 12 is a perspective view of a detail seen in Fig. 11.

As is apparent from the foregoing description of the figures, the invention is carried out in a number of different embodiments, each embodiment being constructed to operate properly in the treatment of a particular type of injury. It will be noted also that the basic principle, however, is carried out in the various embodiments of the invention, many of its details being the same throughout. However, in order that a clear understanding of the invention may be had each embodiment will be taken up separately.

Carrying forward the above idea and directing attention now more particularly to Figs. 1 to 3 inclusive, it will be seen that the reference character 1 designates generally a substantially U-shaped member including spaced parallel arms 2, a connecting bight 3, and a screw-threaded boss 4 carried by the center of said bight. Carried by the intermediate portions of the arms 2 is a right angularly disposed arched or semi-circular wrench 5. Closely associated with this part 1 is a stirrup 6 the extremities of the arms of which are directed outwardly at the angles represented in Fig. 2. This stirrup is adapted to be embedded in a plaster of Paris cast 7 placed about the foot and ankle. The connecting portion of the stirrup is spaced from this cast and a screw threaded stem 8 is connected thereto by way of ordinary nuts. This stem is threaded through the boss 4 and extends beyond the bight portion 3 and carries a turning handle or cross head 9. As is apparent in Fig. 1 the arms 2 are provided with a multiplicity of openings to ac-

5 accommodate fasteners 10 including small bolts and wing-nuts. These serve to adjustably connect a pair of rigid extension struts 11 in overlapping relation with the free end portions of the arms 2. In this connection I
 10 wish to state that these struts 11 will be designated as the primary or main straps for purpose of distinction. These primary struts are provided with offset extremities 12 and spaced inwardly from these are guides 13 provided with set screws 14. These serve a purpose to be hereinafter described. At this time I invite attention to another plaster of Paris cast 15 molded about the lower leg
 15 just below the knee. Embedded in this cast are small metal strips 16 located at diametrically opposite points and carrying outstanding pins 17 extending through the selected openings in the straps 11. Obviously, this
 20 form of the invention is employed upon the lower legs for tibio-fibular fractures, such a fracture being diagrammatically represented in dotted lines in Fig. 2. If desired, another and slightly larger rest 18 of arched
 25 form may be connected to and carried by straps 11.

Attention is now invited to Figs. 4, 5 and 6 wherein it will be seen that the same parts represented in Figs. 1 to 3 inclusive are represented by the same reference characters. However, this form of the invention is amplified by including secondary extension strut 19 fastened to the offset ends 12 of the primary strut 11 due to the fact that
 35 the cast 15^a in this instance is placed above the knee joint.

As shown in Fig. 4 this supplementary strut is provided in this instance with a special appliance 20 including an arm 21 having an offset end 22 fastened to the intermediate portion of the strut 19 and provided at its opposite ends with an arcuate runner which extends through the aforesaid guide 13. The purpose of this arrangement is to
 45 allow the lower part of the structure to be swung in the dotted line position represented in Fig. 6. Under such conditions the set screws 14 are tightened to maintain the movable parts in the extreme dotted line position or any position between the same and the full line position represented in Fig. 6. The curvature of the runners 23 corresponds to the arc of swing of the movable parts of the apparatus. Of course, the angularity or
 55 degree of movement is necessarily governed entirely by the conditions existing.

Considering now the Fig. 7 it will be seen that substantially the same construction just described is shown with the addition of several important parts. First, it will be noted that a substantially U-shaped swinging frame 24 is included and cooperates with the runners 23 as shown in Fig. 8. In addition calipers 25 are clamped upon the knee
 65 as represented in Fig. 7 and are connected

by way of a flexible element 26 such as a cord with a take-up loop 27 carried by the stem 8. Otherwise the invention is as already described.

Referring now to Fig. 11 it will be seen that a further embodiment of the invention is represented. Again, the majority of the parts already described are employed. In fact, there are only two important additions made. One is a curved anchoring strip 28 represented in Fig. 10 and a connecting member 29 represented in Fig. 12. The connecting member 29 is imbedded in the thigh encircling portion 30 of the plaster of Paris cast 31. This is also true of the strip 28, that is, it is also imbedded in the cast and is of a curvature to dispose the apparatus and the leg in the outwardly inclined or angular position approximately represented. Of course, in this instance the cast must be made to encircle the body adjacent the hips.

It will be clear from the drawings that the injury shown in Fig. 2 occurred in the lower leg and under such conditions the brace is applied as represented in Fig. 2. The principle applied is that of extension and traction. Of course, the casts are made to conform to the contour of the portions of the anatomy which they surround in order to equalize the pressure. The action of the screw or stem 8 produces a downward stress or pull upon the foot and ankle and the corresponding upward strain upon the upper portion of the leg. In connection with Figs. 4, 5 and 6, I might state that the structure here shown is used in cases of repair of injuries of the knee joint such as dislocations, fractures, or a post-operative care of ankylosed knee joint. An important point in the care of knee injuries is the ability of a brace to obtain traction sufficient to keep the joint surfaces of the joint apart and at the same time to allow passive motion of the joint through an arc of at least 45°. The desired clearance is provided in the proper adjustment and manipulation of the apparatus herein described. In connection with the bone calipers 25 represented in Fig. 7, I might state that this is used in cases of fracture of the femur anywhere between the junction of the upper and middle third of the knee. The traction in this case is obtained by applying the calipers to the condyles of the femur and traction put on by the screw against the anchorage of the cast applied to the thigh in the manner shown.

It is essential in these cases that the lower leg be not immobilized and for that reason we leave in place the initial lower segment of the brace which incorporates the lower leg and passive motion is obtained by the movement up and down through the arc of 45° as explained. This is essential inasmuch as the injury is above the knee and no traction could be made upon the knee joint

itself nor should the muscles of the lower leg be held at rest by the common straight cast since there is no difficulty in the lower leg.

In connection with Fig. 11 I would state 5 that the assembly here shown is used in injuries of the hip, fracture of the head of the femur either intra or extra capsular. Also in fractures of the upper third of the femur in dislocations or for a mobilization of the 10 joint in tuberculosis. In these cases, the brace is firmly anchored by a body spica. The cast includes the hip and lower abdomen with a pendant down over the upper portion of the thigh. Here, we maintain the proper 15 angulation of the leg so that the broken parts of the upper and of the femur are in apposition.

No doubt, by considering the description 20 in connection with the drawings, a clear understanding of the construction as well as the use and advantages of the invention will be had. Therefore, a more lengthy description is thought unnecessary.

While the preferred embodiments of the 25 invention have been shown and described, it is to be understood that minor changes coming within the field of invention claimed may be resorted to if desired.

I claim:—

30 1. In a limb bracing structure of the class described, a substantially U-shaped member, the arms of which are disposed in spaced parallelism and adapted for disposition on opposite sides of the lower portion of a limb, the bight portion being adapted to be disposed in spaced relation to the foot, a screw-threaded stem carried by the central part of said bight portion, said stem being provided on its outer end with a handle, a stirrup connected to the inner end of said stem and adapted to have its arms imbedded in a 35 cast surrounding the foot and ankle, said arms being provided with apertures, and a pair of apertured primary extension struts connected by fastenings with said apertures, the upper ends of said struts being offset, the 40 portions below said offset ends being formed with guides, set screws carried by said guides, and anchoring strips adapted to be imbedded in a knee cast, said strips being 45 provided with pins for selective reception in apertures in said struts.

2. In a limb brace of the class described, 50 a substantially U-shaped member, a screw-threaded stem carried by the bight portion thereof, a stirrup carried by the inner end of the stem, a handle carried by the outer end of said stem, primary struts adjustably connected to the free end portions of the 55 arms of said U-shaped member, said struts

being provided with offset extremities and in spaced relation to said extremities with guides, secondary extension struts connected with the offset ends, said secondary struts being provided with apertures, a pair of 65 brackets connected adjustably with said secondary struts and including rearwardly and diagonally extending arms terminating in arcuate runners extending slidably through said guides.

3. In a limb brace of the class described, 70 a substantially U-shaped member, a screw-threaded stem carried by the bight portion thereof, a stirrup carried by the inner end of the stem, a handle carried by the outer end of said stem, primary struts adjustably connected to the free end portions of said U-shaped member, said struts being provided with offset extremities and in spaced relation to said extremities with guides, secondary extension struts connected with the offset ends, said secondary struts being provided with apertures, a pair of 75 brackets connected adjustably with said secondary struts and including rearwardly and diagonally extending arms terminating in arcuate runners extending slidably through said guides, together with a U-shaped frame the free 80 ends of the arms of which are connected with the arms of said U-shaped member.

4. In a structure of the class described, 85 a substantially U-shaped member, a screw-threaded stem adjustably mounted upon the bight portion of said U-shaped member, said stem being provided with a handle, extension struts connected with the end portions of the arms of said U-shaped member, means whereby said struts may be anchored to a cast upon an upper portion of a limb, calipers, and a flexible connection between the 90 calipers and said stem.

5. In a limb brace of the class described, 95 a substantially U-shaped member, a screw-threaded stem adjustably mounted on the bight portion of said member, said stem being provided with a handle, a stirrup connected with the inner end portion of said stem, primary extension struts adjustably connected in overlapping relation to the arms of said U-shaped member, the upper 100 ends of said struts being offset, a pair of secondary extension struts connected with said offset ends, a bracket for anchoring the free end of one of said secondary extension struts to a thigh cast, and a bowed strip adjustably connected with the free end portion of the remaining secondary strut and adapted 105 to be anchored in said thigh cast.

In testimony whereof I affix my signature.
CHARLES HARRISON PIERCE.
